UNITED STATES PATENT OFFICE

2,535,737

TRAVERSE

Hilyard C. Howsam, Chicago, Ill., assignor to
 Hubbard Spool Co., Chicago, Ill., a corporation
 of Illinois

Application January 17, 1946, Serial No. 641,782

1 Claim. (Cl. 242—123)

1

The present invention relates to a reel construction and has to do with a traverse and a method of making the same.

In connection with the manufacture of reels or spools for supporting wire, cable or other products to be wound for shipment and use, the traverse manufacturer makes the traverses and ships them as such to the reel user who applies heads to the traverses to complete the reels.

It has happened, in the past, that when the traverses are being shipped, loaded in a car on their flanged ends, that an abnormal shock may be imparted to the car, causing its load to shift and in such shifting, some of the traverses have been bent into other than cylindrical form, thus rendering them incapable of use.

Experience has demonstrated that when the traverses are made of single thickness material, sometimes the heads pull off from the traverse flanges, as the single thickness metal about bolt holes in the flanges tears under unduly severe use or treatment.

Various and sundry means have heretofore been devised for overcoming these objections.

The present invention overcomes the objections existing at the present time and has for an important object the provision of a novel method of making a traverse.

Another object of the present invention is to provide a traverse having reinforced flanges integrally formed from the material of which the traverse is made.

A further object of the present invention is to provide a traverse having integral annular reinforcing means at its ends for preventing collapse during shipment.

Another and further object of the present invention is to provide a traverse in which the reinforcing parts are formed integrally from the material of which the body or barrel of the traverse is made.

Another and yet further object of the present invention is to provide a single thickness traverse having double thickness end flanges and other reinforcing means adjacent the flanges, all formed from single thickness stock.

The above, other and further objects of the present invention will be apparent from the following description and accompanying drawing.

The accompanying drawing illustrates an em-

2

bodiment of the present invention, and also suggests the method of manufacture, and the views thereof are as follows:

Figure 1 is an isometric view of a traverse showing a head applied to one end.

Figure 2 is an isometric view of the blank from which the traverse is made.

Figure 3 is a sectional view through a traverse after the ends of the blank have been secured together in cylindrical form.

Figure 4 is a schematic view showing certain steps in the method of manufacture, and illustrating how the double thickness flanges and reinforcing means adjacent the flanges may be formed.

Figure 5 is a central sectional view through a completed traverse.

Figure 6 is a fragmental sectional view through a traverse showing one method of welding when the traverse is made of two pieces of material.

Figure 7 is an end view of a traverse made from two semi-cylindrical parts.

The drawing will now be explained.

Referring to Fig. 1, a one-piece traverse is designated as A, and an end structure B is shown as applied to one end of a traverse.

The traverse A is made from a piece C of metal blanked from suitable stock with its length substantially that of the circumference of the finished traverse. The longer margins are folded over as at 15 and 16, lengthwise of the body of the piece. The piece C is then formed into cylindrical shape and the unfolded ends are welded together making a seam 17.

Thereafter the folded portions 15 and 16 are subjected to pressure action to flatten them against the body of the traverse, and also smooth out any wrinkles that may have been formed by the rounding of the piece into cylindrical form.

Referring to Fig. 4, schematic means are shown for flattening the folds 15 and 16.

Referring to Fig. 4, a pressure roller 18 suitably mounted and supported to be rotated by a stem 19 bears against the fold 15, the body of the transverse course being suitably backed, whereupon the fold 15 is flattened against the body of the traverse. When the fold has been suitably flattened, other means, such for example as a roller 20, is moved against the outer surface 50 of the traverse, adjacent an end, to bend over

the end, substantially at right angles to the axis of the traverse, to provide a flange 21. The bend is made intermediate the marginal portions of the fold 15, that is to say somewhere within its height, so that the resulting structure provides a double thickness flange 21 and an annular ring 22 against the inner surface of the traverse body adjacent the flange 21. The ring 22 reinforces the traverse against collapse when pressure is suddenly applied against its outer surface.

After the flange 21 has been made as described, the opposite end of the traverse body is subjected to the same action to produce a similar flange at the other end. After the flanges are formed, they are punched or otherwise processed to provide bolt holes 23. Fig. 1 and Fig. 7 show four bolt holes for a flange but it is to be understood that more or less may be used depending on conditions of use of a reel, its size, and the load it is intended to support.

It will thus be noted that I have provided a traverse, and also a method for making the same, whereby a reinforced traverse is made from a single piece of material, the material being processed to provide double thickness end flanges and double thickness annular supports of the traverse body adjacent the flanges.

A traverse constructed in accordance with the present invention is strong, rugged, will withstand heavy abuse, and is one in which the end structures B may be securely attached without fear of accidental looseness or loss.

It might be desirable, under certain circumstances, to make the traverse of two pieces of material which can be done by making two halves or bodies, as illustrated in Fig. 6, and welding the half bodies together along circumferential seams 24.

It might be desirable to make the traverse of two semi-cylindrical parts, in which event the two parts D and E should be welded together as indicated in Fig. 7 by the seams 25 and 26.

The traverse of the present invention, as will be noted, possesses sufficient rigidity against body collapse due to forces imposed on the traverses while being shipped, and at the same time pos-

sesses sufficient strength in the end flanges to resist tearing out of the bolts, so that a reel made with such a traverse will be capable of standing heavy abuse as the reel with its load is moved about in service.

The method of the present invention has to do with ways and means for reinforcing a traverse to provide double thickness flanges and annular reinforcement adjacent the flanges, formed from the same material as the body of the traverse is formed, so that the resulting structure is strong, rigid and rugged.

It will, of course, be understood that various details of construction may be varied through a wide range without departing from the principles of this invention and it is, therefore, not the purpose to limit the patent granted hereon otherwise than necessitated by the scope of the appended claim.

I claim as my invention:

A traverse for a reel comprising a cylindrical body portion of single thickness stock, radially inwardly directed double thickness annular end flanges formed integrally with and of the same stock as said body portion, and annular reinforcing rings extending about the inner periphery of said body portion at each extremity thereof, said rings being formed of the same stock as said flanges and said body portion to reinforce that body portion edge adjacent said flanges by cooperation with said body portion to present a double thickness terminal annular edge joining said flanges to said body.

HILYARD C. HOWSAM.
